Attorney.*

UNITED STATES PATENT OFFICE.

MILTON F. WILLIAMS, OF ST. LOUIS, MISSOURI, ASSIGNOR TO WILLIAMS PATENT CRUSHER & PULVERIZER CO., OF ST. LOUIS, MISSOURI, A CORPORATION OF MISSOURI.

LIP-PLATE FOR GRINDERS.

1,282,156. Specification of Letters Patent. Patented Oct. 22, 1918.

Application filed May 10, 1918. Serial No. 233,613.

To all whom it may concern:

Be it known that I, MILTON F. WILLIAMS, a citizen of the United States, and residing at St. Louis, State of Missouri, have invented 5 certain new and useful Improvements in Lip-Plates for Grinders, of which the following is a specification.

This invention relates to certain new and useful improvements in lip plates for the 10 hoppers of grinders, the peculiarities of which will be hereinafter described and claimed.

The main object of my invention is to provide means for preventing the hammers 15 of the grinder throwing out of the hopper the feed supplied to said hopper. A further object is the collecting in a suitable pocket certain foreign particles always found in feed from the field, such as pieces 20 of metal, wire, gravel and such like.

In the accompanying drawings on which like reference letters indicate corresponding parts, Figure 1 represents a vertical sectional view of part of a grinder, its hopper, 25 and my improvements applied thereto;

Fig. 2, a separate detail perspective view of a pocket lip plate, exemplifying my invention in its preferred form;

Fig. 3, a sectional view of the device shown 30 in Fig. 1 on the line X looking in the direction of the arrow; and

Fig. 4, a similar sectional view to Fig. 3 taken at Z through the grooves in front of the inclined slide plate of Fig. 1.

The letter A designates the shaft of a 35 grinder on which are mounted disks B provided with pivoted hammers C carried by hammer rods D and rotating in the direction of the arrow Fig. 1. These parts are 40 called the cylinder and are suitably mounted in a casing E provided with a hopper integrally or otherwise mounted above the said casing E.

This top position for the hopper is preferred to the side position in grinders of 45 this class which are adapted to grind velvet beans, cow peas and like material by receiving the feed material from above. This hopper therefore consists of a vertical wall F and 50 a slanting upwardly flaring wall G between side walls H. The vertical wall F at the right is nearly above the central shaft A, while the slant wall G is on the opposite side of said shaft and meets the casing E 55 farther down or nearer to the horizontal cen-

tral plane of the shaft. The rotation of the hammers is from the right to the left,—or from the wall F at the near side of the hopper toward the slant wall G on the far side of said hopper. The supply of feed 60 therefore coming from above, has a tendency to be driven slanting upward and outward at the top of the hopper, and especially toward the corner of the hopper where the top of the slant wall G ends. I have therefore provided a lip plate located at the top of this slant wall G, and covering more or less of the top opening of the supply hopper by a cross plate portion I, having a vertical depending plate portion J at its inner 70 edge. A hood open at the bottom is thus formed at this far side of the hopper. The plate I extends inwardly across the hopper so that the ends of said plate rest upon the side walls H. The wall J however extends 75 downwardly between said walls H and preferably in simple contact therewith and having its lowest edge depending nearly into the path of those particles that, having entered the hopper, have been driven upwardly 80 toward the slant wall G by the impact of the hammers. This lowest portion of the wall J is located a suitable distance from the slanting wall and forms, with the side walls H, slanting wall G, and the inwardly extending wall I of the lip plate itself,—a cov-

ered hood that is open inside the hopper. The construction thus described pertains to the main object of my invention. The outer edge of the plate I rests above the top of the wall G, and is preferably provided with lugs i coacting with lugs g on the outer and upper side face of said wall G, by which a hinge connection is provided for the plate I and its connecting vertical wall J, the bottom edge of which vertical wall preferably carries an upwardly inclined ledge K, which forms a pocket below the plate portion I and between the wall J and the wall G. This inclined ledge K is likewise an easy fit between the walls H, and being supported by the wall J may be thrown up and around in the arc of a circle about the hinge of the plate I, as indicated by the arrows and the dashed line position of the pocket plate Fig. 1. 105 Thus the second object of my invention is attained.

At the opposite side from the pocket plate, and extending from the top of the wall F downward in a slanting direction toward the 110

wall G, is a slidable plate L mounted in grooves in the side walls H. This slide plate L has a lip M at its bottom edge, reversely inclined as shown in Fig. 1. The upper edge 5 of the plate L has a horizontal lip N, bent to the right as shown and adapted to serve as a handle to lift the plate, as indicated by dotted lines in Fig. 1, to any adjusted position in the guiding grooves. A thumb 10 screw O opposite one groove in the side wall H, fixes the slide L in any desired adjusted position.

This slide L serves as the bottom of the supply hopper and is adapted to deliver the 15 feed material more or less over the center of the shaft, and therefore directly upon the top of the rotating hammers, according to its adjustment in its grooves. The effect of the hammers upon the entering feed is 20 therefore varied. For instance, when the slide L is adjusted to the position shown by dotted lines the hammers C will tend to drive the feed material more nearly upward or on a steeper slant to the horizontal than 25 when the slide is in the position shown by full lines. Any foreign matter that is heavier than the feed, such as pieces of metal, will be driven by the hammers across into contact with the slant wall G, on which 30 they will impinge at a greater or less angle to the normal and will shoot upward under the slant wall K, up and over it, being deflected by the plate I into the pocket below 35 said plate. The lighter feed is not so strongly affected by the hammers as the heavier metal particles, although particles of the feed itself tend to fly out of the hopper when this deflecting lip plate is not used. The space between the vertical wall 40 F and the inclined slide L, is subject to the suction effect of the hammers passing below it, whereby a certain rarefaction of the air in the chamber is produced. The backwardly inclined lip M deflects the feed and 45 especially the dust particles, so that they are not so readily driven upward out of the hopper.

While I have described and shown the plate K adapted to form a pocket, it is evident that this inclined plate K may be 50 omitted or not required in certain kinds of material; when omitted the vertical wall J will deflect the material driven by the hammers against the slant wall G downward 55 again and prevent them flying out of the top of the hopper. In some cases this is all that is necessary, while in others it is desirable to provide a pocket for the collection of foreign material as above mentioned.

I have shown in Fig. 3 a modified pocket 60 in which the slant wall K' and the vertical wall J' as well as the top plate I', are cast integrally with the side wall H. In order to release the foreign material from this 65 pocket, I have provided a slant bottom P

Fig. 3, inclined upward from each side wall H, in which side wall is an opening Q protected by a cover R pivoted at one edge, as shown in Fig. 3 and indicated in Fig. 1. This provides for the discharge of accumulated metal or gravel in said pocket when it is formed as shown in Fig. 3.

Thus the covered holes Q in the sides of the hopper, or the hinged connection for the plate, provide means for clearing the 70 pocket behind the inclined wall K'—K respectively, when such form is used.

I claim:

1. The combination with a machine of the character described having rotary beaters and a hopper above said beaters provided with a slanting upwardly flaring wall between the side walls and on the far side of the hopper, of a lip plate comprising a wall extending from the top of said slanting wall inwardly and downwardly within the hopper, and having its lowest edge depending nearly into the path of the entering material that is driven upwardly by impact with said hammers, and separated 80 from said slanting wall by an open space, the lip plate thus forming with the sides and slanting wall a covered hood open inside the hopper for deflecting that portion of the feed that the hammers tend to throw 85 out of the hopper.

2. In a machine of the character described, the combination with a casing, a set of rotary hammers mounted therein, and a supply hopper located above said hammers, of 100 a horizontal lip plate hinged at one edge to the adjacent wall of said hopper, and provided at its opposite edge with a vertical wall depending between the side walls of the hopper, and having at the bottom edge 105 of said vertical wall an upwardly inclined ledge plate forming a pocket with an opening within the hopper to receive the material driven by said hammers thereinto.

3. The combination with a machine of the character described having rotary beaters, and a hopper above said beaters provided with a slanting, upwardly flaring wall between side walls and on the far side of the hopper, of a lip plate comprising a wall 115 extending inwardly and downwardly within the hopper from the top of said slanting wall forming a hood with an opening within the hopper, and then inclined upwardly and toward said slanting hopper wall forming a pocket in said hood, substantially as described.

4. The combination with a machine of the character described having rotary beaters, and a hopper having slanting grooves in the side walls above said beaters, and provided with a hood projecting from the far side inwardly and downwardly, and then upwardly toward said far side forming a covered pocket opening within the hopper, and 125 130

a plate slidingly mounted in said slant grooves to form an adjustable bottom for said hopper and thus vary the upward direction of a portion of the entering feed 5 that is driven by said beaters into said hood and its pocket.

In testimony whereof I have affixed my signature in the presence of two witnesses.

MILTON F. WILLIAMS.
